UNITED STATES PATENT OFFICE

OSCAR J. OLM, OF ST. PAUL, MINNESOTA, ASSIGNOR TO QUALITY PARK ENVELOPE COMPANY, OF ST. PAUL, MINNESOTA, A CORPORATION OF MINNESOTA

ENVELOPE

Application filed October 7, 1926, Serial No. 140,067. Renewed May 11, 1932.

My invention relates to envelopes, wherein it is desired to provide an envelope particularly adapted to a construction to simplify the manufacture, and to assist the user of the envelopes in sealing the same without tearing the envelope at the sealing flap, and more particularly in providing an extremely simple construction for an envelope. A feature of the invention resides in providing an envelope particularly adapted to that class of envelope used for mailing matter, so that first class mail can be carried along with other mailing matter of another class. This permits mail having an analogous relation to be sent out together and received at the same time by the party to whom it is addressed.

An important feature of my invention resides in the particular formation of the died out blank of the envelope which permits the necessary flaps to be cut out without waste of material and without projection of the flap for one of the compartments of the envelope. The non-projecting flap of the died out formation of this envelope is cut along the marginal edge of the overlap of the sides of the envelope, so that an envelope died out of the formation I have illustrated can be more readily and easily handled in folding and pasting the same, thus permitting these envelopes to be made very rapidly on machinery designed to handle the same.

It is also a feature of my invention to provide an envelope wherein the non-projecting flap is made along the marginal edge of the overlap of the envelope, which forms one wall of the envelope, by notching out a portion of the marginal edge to provide a space between the flap and the marginal edge which is pasted down. This space is very important, because it permits the portion of the margin which is pasted down to form the overlap to be attached securely or pasted, without pasting the flap or the edge thereof, as the flap is spaced away from the edge of the margin, which is pasted down sufficiently to prevent any possibility of the pasting of the unprojecting marginal flap, and thereby permitting my envelope to be made up very rapidly.

My invention constitutes the notching out of a marginal nonprojecting flap, the notched

out portion having rounded or arcuated cuts to prevent any sharp corner or pointed cuts, which would cause the flap to easily tear at the depth of the cut. In other words, the depth of the cut is rounded to strengthen the flap, and prevent the same from easily tearing to the depth of the cut which is necessary to make the same.

Further, this form of notching out the margin to form a flap for the envelope provides an envelope which may be used for two classes of mailing matter, the non-projecting flap acting as the closing flap for one class of mail matter, while the ordinary projecting flap may be used to close the other compartment of the envelope.

By notching out a portion of the marginal edge, I also provide an indication to show where the compartment which is formed on the side wall of the envelope for mail matter is located, and by printing a color on the envelope, this notched out portion is very clearly indicated, and is provided to show where the second compartment of the envelope is located. This second compartment is considerably smaller than the main portion of the envelope, thus it is quite an advantage to construct the envelope in the died out formation which I have illustrated.

These, and other features, together with details of the invention will be hereinafter more fully and clearly set forth.

In the drawing forming a part of this specification:

Figure 1 is a side view of my envelope folded correctly.

Figure 2 is a section on the line 2-2 of Figure 1.

Figure 3 illustrates the died out or geometric development of my envelope in its proper form.

Figure 4 illustrates my envelope folded and the closing flap for the compartments sealed and folded in to enclose the contents within the compartments of the envelope.

In the drawing, my envelope A is of a very simple nature, and is adapted to be cut out of a sheet of paper in the died out formation illustrated in Figure 3.

The died out formation of my envelope in-

cludes the center portion 10, the projecting flap 11 on one side of the center flap and a projecting flap on the opposite side of the center or body portion of the envelope. The flap 11 is a long flap which is practically of the same width and length as the center or body portion 10. This flap 11 is adapted to be folded on line 13 over on to the portion 10 of envelope A, while the flap 12, which is of a shorter or narrower width than the flap 11, is adapted to be folded on the line 14 over on to the flap 11.

Flap 12 provides the marginal edge 15 of the overlap of the envelope A and has a marginal portion 16 of paste or glue together with an inwardly projecting portion of paste 17, extending from the marginal portions of paste 16 toward the folded line 14 as illustrated in Figure 3. Thus, when the flap 12 is folded over on to the flap 11, the glue portions 16 and 17 are adapted to be secured to the flap 11. The inwardly projecting portions of paste 17 are spaced apart to provide a central portion 18 in the flap 12 which is adapted to constitute one wall of a compartment for the envelope A. The other wall of this compartment is formed by the inwardly projecting free end of the flap 11. Thus a compartment for mailing matter is formed 30 which is separated from the main compartment formed by the center portions 10 and the overlying flap 11.

I provide a marginal non-projecting closure flap 20 for the portion 18 of envelope A by notching out portion 21 of the marginal edge 15. The notching out portion 21 is formed with arcuated cut portions at 22 so that the depth of the cut of the notched out portion 21 is rounded and thereby prevents tearing of the flap 12 at this point when it is in use.

The flap 20 is adapted to be a pasted marginal surface 24 while the center portion 18 may be formed with a window or address 45 opening 25 which may be covered by translucent tissue paper or other suitable material, or may be left open as in the case of some forms of envelopes.

It is important to note that in the manufacture of envelope A, that to make them a profit it is necessary that they should be made on an envelope machine, that is they should be pasted and folded on a machine. Therefore the notched out portion 21 is of great 55 importance in my invention as it provides a space between the paste 16 of the marginal edge 15 and the pasted surface 24 of the closure flap 20. By providing this space, I prevent the accidental pasting of any portion 60 of the closure flap 20 in the manufacture of these envelopes A and the flap 20 may be provided with the necessary adhesive 24 which is allowed to dry so that it may be used afterwards for sealing the compartments made by 65 the portion 18 in the flap 12.

The non-projecting marginal flap 20 is of extreme importance in my invention as it provides a closure flap for the compartment of my envelope A which may be used for first class mail matter, and this type of envelope 70 can carry the one address visible through the opening 25 with the added advantage of carrying two classes of mail matter at different rates of postage.

I provide a short end flap 26 which is 75 adapted to be folded and pasted down on the flaps 11 and 12 to close one end of the compartment of envelope A, and on the other end of the envelope A, I provide a longer flap 27 which may be tucked in as illustrated in 80 Figure 4, to permit examination of the contents of the large portion of the envelope. The notched out portion 21 forms an indicating space so as to readily indicate a separate envelope flap for the portion 20, and by printing a color such as 28 on a portion of flap 11. A distinct indication can be made apparent on the envelope to clearly show, even when the flap 20 is sealed as in figure 4, that another compartment is situated in the envelope A. 85 By cutting out the notch 21, the non-projecting flap 20 may be more easily engaged and sealed, so that together with the spacing of the respective edges of the margin 15 and the end edges of the flap 20 away from each 90 other, I provide an envelope structure wherein a non-projecting flap may be used with a very distinct advantage, which may be readily appreciated in the envelope industry and art.

In accordance with the patent statutes I have described the principals of operation and formation of my envelope, and while I have illustrated their particular design, I desire to have it understood that this is only 10 suggestive of a means of carrying out my invention, and that same may be applied to other use within the scope of the following claims.

I claim:

1. An envelope including overlapping sides adapted to form one wall of the envelope and a non-projecting closure flap formed in the marginal edge of one of the sides, said non-projecting flap being constructed by cutting away portions of the marginal edge to permit sealing the marginal edge on either side of said flap with said flap unsealed.

2. An envelope including overlapping 1 side flaps constructing one wall of the envelope, a compartment formed in the said wall with the overlapping sides, and a non-projecting marginal flap formed by notching out portions of the margin of the overlapping 1 sides of the envelope with arcuated portions at the corners and depth of the notched out portions.

3. A two compartment envelope including a main body portion forming one compart- 1

ment, overlapping sides adapted to form one wall of the main body compartment, a compartment formed by the overlapping sides therein, and a non-projecting marginal flap 5 having end portions spaced by an open portion from adjacent portions of the margin of the overlapping flap.
